UNITED STATES PATENT OFFICE.

EARL VANDERLIP, OF ALTO, MICHIGAN. ASSIGNOR OF ONE-HALF TO ARTHUR O. BICKFORD, OF ALTO, MICHIGAN.

GASOLENE-ENGINE.

957,278.

Specification of Letters Patent. Patented May 10, 1910.

Application filed March 29, 1909. Serial No. 486,641.

To all whom it may concern:

Be it known that I, EARL VANDERLIP, a citizen of the United States, residing at Alto, in the county of Kent and State of Michigan, have invented certain new and useful Improvements in Gasolene-Engines, of which the following is a specification.

My invention relates to improvements in gas, and gasolene engines for running small machinery, and its objects are: First, to so regulate the motion of the engine that it may be utilized for running electric lights. Second, to provide for producing the greatest possible amount of power with the least possible consumption of gas, and, third, to provide a means whereby the pressure of air in the gasolene tank may be absolutely controlled. I attain these objects by the mechanism illustrated in the accompanying drawing, in which—

Figure 1 is a side elevation of a gasolene engine, showing the several elements of my invention in place, and the gasolene tank in section to show the relative position of the air and gasolene with their respective conveyer pipes. Fig. 2 is a plan of the same, showing the position of the air chamber between the base of the engine and one of the fly-wheels. Fig. 3 is a sectional elevation of the air pump, the air chamber, and the several valves connected therewith, and the manner of controlling them. Fig. 4 is a side view of the governor arm and box, with the box shown in section to show more plainly, the manner of governing the flow of gasolene and air to the cylinder. Fig. 5 is a sectional plan of the fly wheel and the governor cone in place on the shaft to show the manner of attaching and operating the governor, and 40 with the governor box in section to show the position of the aperture through the governor arm.

Similar letters refer to similar parts throughout the several views.

In the accompanying drawing A represents the cylinder, B, the cylinder frame or base, C, the shaft, and C', the fly wheels of an ordinary gasolene engine.

To carry out my invention, I make provisions for mixing the air and gasolene before it reaches the cylinder, and, for this purpose it is necessary to provide some means whereby an actually even pressure may be maintained in the air and gasolene tank K, and for this purpose I provide an air pump, L,

that may be set in any available position. I have here indicated it as located directly under the main shaft C at the left hand side of the engine, to be operated by the eccentric L'', in the usual manner of transmitting motion by the use of an eccentric. Connected with this pump is an air chamber M, and connected with the pump and the air chamber are the several valves, L', M' and P'', which are operated as follows: When the pump piston L'' is being moved upwards, the valve L is opened and air rushes in around it to fill the vacuum formed in the pump cylinder L by the withdrawal of the piston. When the piston returns on its downward stroke, the pressure of air in the cylinder L will force the valve L', open against the tension of the spring o'', and the air will be forced through the orifice into the air chamber M, and will be forced from this chamber, through the discharge pipe m into the upper portion of the gasolene tank K, as at k', above the gasolene k, whence the pressure of the air in this tank will force the gasolene out through the pipe i, and the air will be forced through the pipe i', and the two are mixed in the pipe I and pass through the governor II and the pipe I' into the cylinder A at J', just forward of the engine piston when it is at the extreme backward position of its stroke, as indicated by the dotted lines r r in Figs. 1 and 2.

With the pump L continually forcing air into the gasolene tank, without some governing device to control it, the pressure would be likely to become excessive, with the danger of flooding the engine, or, at least, of forcing an over-supply of gasolene into it, and to obviate this I have provided a valve, P'', in the air chamber M, in position and so constructed, and operated that an excessive amount of pressure in this chamber will open this valve and allow the surplus air to escape through the small apertures s s, and thus relieve the pressure in the gasolene tank until it has reached its normal pressure, when the valve P'' will be closed by the spring P, which spring may be adjusted to allow the valve P'' to be opened and closed at any desired pressure. To further insure the proper governing of the pressure in the air chamber and gasolene tank I pivot a lever O, upon a post O', with one end pivotally connected with the valve stem P', and the other end in position to actuate the valve 112

stem p , so that when the valve l'' moves to the left the connection of the stem p' with the lever O , at o , will move this end of the lever to the left, and the other end of the lever, having contact with the valve stem p at o' , will force this valve stem, and the valve l , inward against the tension of the spring P' , and allow air to flow out of the pump cylinder without flowing into the air chamber M , as the piston L' moves downward, or toward the air chamber, thus greatly aiding to hold the pressure in the chamber M and the gasoline tank K , to the normal condition.

The construction and operation of valves hereinbefore described will govern the motion of the engine very closely, but not close enough to warrant its use for producing a steady light from an electric light dynamo, and to further overcome the danger of producing a flickering light I have placed a second governor, H , upon the engine, which operates as follows: I place a sliding cone, D , upon the shaft C , and actuate it by means of governor balls or weights N , which are mounted upon arms n on the hub C'' of the fly wheel C' , in such a manner that the rotary motion of the fly wheel will cause them to spread against the tension of the springs N' . The angle arms N' , which are integral with the weights N , are connected with the cone D by links n' , so that when the balls or weights N are forced apart the cone will be drawn toward the hub C'' .

The governor box H is set in the line of the pipes I I' , so that the air and gasoline passing from the tank K must pass through this box laterally, or, vertically. To complete this governor I place an arm H' in position so that one end passes into the box H in the line of flow of gasoline through the pipes I I' , and I place an aperture h' through this end of this arm so that the gasoline and air may readily pass through the box from the pipe I into the pipe I' . This pipe is supported in position so that the shoe D' will be forced against the cone D , by the spring h , and when the cone D is in its normal position, the hole h' through the end of the arm H' will be in exact position with the pipes I and I' , so that the gasoline may flow freely, but as the cone is drawn toward the hub C'' the arm H' will be moved farther into the box A and the hole h' will be carried by the openings of the pipes I I' and correspondingly cut off the flow of gasoline to the engine, thus, in connection with the air pressure from the air pump L , I am enabled to govern the motion of the engine to a nicety, and to avert the danger of an excessive explosion at any time when the engine is being operated, as, for instance, in the ordinary engine, when the engine passes above a certain velocity one or more explosions are sometimes skipped, and when an explosion again occurs

it is likely to be an abnormal one, which endangers the working parts of the engine, but with my double governor attachments such is impossible as the least variation of the motion of the engine will be caught and checked by one or the other of the governors and the gasoline is so held back that an abnormal explosion is impossible.

J and J' represent valves in the line of the pipes I and I' , for the purpose of opening and closing these pipes to the flow of gasoline, for starting and stopping the engine.

The electric battery F is connected with the sparking plug F' and the insulated plug F'' , by the circuit wires f f' , and the circuit is completed by the wire f'' , which passes back to position directly over the shaft C where it is connected with the plate e , which is insulated from the actuating rod E , as indicated at e' , so that there can be no possible danger of contact between the two. To the plate e I attach a contact spring d' in such a position that when the rod E is drawn forward to the position indicated in Fig. 1, the back wing of the spring d' will be engaged by the contact plug d , with each revolution of the shaft C , and the electric circuit will be completed at a point where it will ignite the gasoline in the cylinder A at a point that will cause the engine to run in one direction, as, for instance, in a direction to cause the fly wheels C' to revolve in the direction of the arrow in Fig. 1, but with the rod E thrown back to the dotted lines at the back end of the rod, which is accomplished by throwing the lever G over to the position of the dotted lines in Fig. 1, the contact will be made in position to cause the engine to run in the opposite direction from that indicated by the arrow.

The contact d is integral with the cone D and as the rod E is very narrow, or thin, if the engine acquires too high speed the cone will be drawn far enough toward the wheel hub C'' to draw the contact plug d from under the contact spring d' and thus assist to govern the speed of the engine. If it is found that there is not sufficient air mixed with the gasoline at the conjunction of the pipes I and I' , more air may be allowed to enter at j , as the gasoline is passing into the engine cylinder. It will be seen that gas is taken into this engine cylinder at the back stroke of the piston, so that compression takes place as the cylinder moves forward, thus giving me the advantage of a four cycle action with a two cycle engine. If desired the valve l'' may be made to seat itself on the seat at S and thus shut off the flow of air from this source, which will hold the pressure in the chamber M longer as the pump piston can force no air into the chamber so long as the valve l is held open by the pressure in the chamber against the valve l'' .

This is, really, desirable, as it allows of a more gradual lessening of the pressure and has a better effect in the gasoline tank.

What I claim as new and desire to secure 5 by Letters Patent of the United States, is:

1. In combination with the cylinder, shaft, and igniting attachments of a gasoline engine, an air tight gasoline tank, a pipe leading from the tank to the cylinder, means for 10 forcing air into said tank under pressure and for governing the pressure, a pipe leading from the air in the tank to the pipe that leads to the cylinder, a governor box in the line of the gasoline pipe, an arm entering 15 the box and having an aperture through it in the line of the gasoline pipe, means for automatically actuating said arm to open and close the pipe between the tank and the cylinder, a contact plug connected with the 20 shaft, a contact spring in position to be actuated by the contact plug to induce an electric circuit.
2. In combination with a gasoline engine cylinder, its main shaft and electrical connections, an air tight gasoline tank, a pipe leading therefrom to the cylinder, a pipe 25

conducting air from the tank to the gasoline pipe, a governor box in the line of said gasoline pipe, an arm entering said box and having an aperture through it in the line of 30 the gasoline pipe, a cone slidably mounted on the shaft, means for automatically sliding said cone on the shaft when the shaft revolves, a shoe on the governor arm to engage the cone and give longitudinal movement to 35 the arm to open and close the passageway in the gasoline pipe, a contact plug on the apex of the cone, a rod in the electrical circuit of the engine, a spring on said rod in position to engage the contact plug as the cone revolves with the shaft and to be disconnected therefrom when the cone is moved from under the rod, and disconnect the electric circuit when the motion of the engine is above normal.

Signed at Grand Rapids Michigan March 16, 1909.

EARL VANDERLIP.

In presence of—

ARTHUR O. BICKFORD,
I. J. CILLEY.
